United States Patent Office.

EDWARD SULLIVAN, OF PITTSBURG, PENNSYLVANIA.

Letters Patent No. 63,672, dated April 9, 1867.

IMPROVEMENT IN PISTON PACKING.

The Schedule referred to in these Letters Patent and making part of the same.

TO ALL WHOM IT MAY CONCERN:

Be it known that I, EDWARD SULLIVAN, of Pittsburgh, in the county of Allegheny, and State of Pennsylvania, have invented a new and useful Improvement in "Piston-Heads;" and I do hereby declare the following to be a full and exact description thereof, reference being had to the accompanying drawings and to the letters of reference marked thereon.

The nature of my invention consists in the construction and arrangement of the different parts of piston-heads of steam engines in such a manner that the packings are expanded by the pressure of a portion of the steam admitted to the cylinder, and balancing the weight of the head by the pressure of said portion of steam.

To enable others skilled in the art to make and use my invention, I will proceed to describe its construction and operation. In the accompanying drawings, making part of this specification—

Figure 1 is a longitudinal section of a piston-head with the packings and valves in their proper position.

Figure 2 is a transverse section of the same, cut through the line *r*, fig. 1.

Figure 3 is an end view of the piston-head.

Figure 4 is an edge view of one of the packing-rings, showing the arrangement of the plates covering the joint of said ring.

Figure 5 is a top or side view of the said ring, showing the arrangement of the plate and the groove in the ring for the purpose of lubricating by means of the steam contained in it.

In fig. 1 *J*, *B*, and *P* constitute a piston-head of the ordinary construction intended to receive spring packing. *R* is the piston-rod; *m* the follower; 4, 5, and 6, the packing-rings, with the recesses in them for balancing and lubricating; and *x x* are the self-operating valves for the admission of steam to the interior of the piston-head. The piston-head I make in the usual manner, with wings or ribs radiating from the centre to receive the bolts used for holding the followers to their place, which rest on the pressure-disk *B*, (being part of the head,) thereby relieving the packing-rings from any pressure that comes on the followers. The packing-rings I make of any suitable material, and fit them together as shown in fig. 1. Upon the outside of two of them, 4 and 6, I make a groove, *f*, about one-fourth of an inch wide, and the same in depth. Between each two adjoining rings on the inside I make the recess *C*, which also extends around the ring, and of about the same proportion as the former. Upon the outside of the middle ring 5 I form the recess *A*, (see figs. 1 and 3,) and connect said recess with the opening in the interior of the head by means of the hole marked 2, fig. 1. The rings are cut diagonally across their face, as shown at the point marked 3, fig. 5, and the cut or joint is covered by the two plates *g* and *h*, which are secured one to each part of the ring by suitable rivets, (see fig. 4.) The union of the edges of the two plates is the arc of a circle, the radius of which is equal to the distance from the point at which the plates join to the extreme outside of the ring directly opposite, so that when the rings wear, and the joint at the point marked 3 becomes wider, the edges of the plates *g* and *h* will always coincide and make a steam-tight joint. The valves *x x* consist of a short cylinder, in which there is fitted a piston, 1, the ends of which present different areas to the action of the steam; the difference of the areas being in proportion to the required difference between the pressure in the cylinder and that within the head, that is, if the pressure in the cylinder be one hundred pounds to the square inch, and it is required to have twenty within the head, the area should be as one is to five, that is to say, the area of the piston upon which the steam within the interior of the head acts should be five times as great as that upon which the steam in the cylinder acts, so that when the steam which enters the head exceeds a pressure of twenty pounds to the square inch the piston will move and prohibit the entrance of any more steam. At the point 9 upon the valve or cylinder *x* there is made a number of holes, which enter the small bore of the valve, and which are intended to admit the steam into the interior of the head when the piston is moved past them by the pressure of the steam in the cylinder. 7 is a cap, which screws upon the end of the valve *x* for the purpose of keeping the piston 1 in its chamber. Said cap has an opening through it to admit steam to the end of the piston 1.

Having the parts made as described, I put them together in the following manner: The ring 6 I grind to its proper bearing upon the piston-head with emery or other suitable substance, and fasten it there by the small pin *i*. The rings 4 and 5 I now grind, and fasten to their place upon each other and upon the ring 6 in the same manner, the object of these pins being to keep the rings from turning around and bringing two or more

of the cuts or joints 3 opposite each other. I now fit the follower to its place upon the pressure-disk B and ring 4 in the same manner as the other rings, and having the valve-chambers *x* *x* in their proper places in the interior of the head, one in the part of the piston P, and the other in the follower, I fasten the follower to the head by means of the bolts *n* *n* *n*, which completes the job, and leaves the head, after being placed in the cylinder, ready for operation, which is as follows:

Steam, being admitted into the cylinder on the side of the head marked P, acts upon the piston 1 in the valve-chamber *x*, and moves it back past the holes marked 9, and into the position shown in the valve-chamber which is in the follower, thus allowing the steam to enter the interior of the piston-head and act upon the other end of the piston 1. When the steam has attained the desired pressure within the head it will again move the piston 1 in both of the valve-chambers, and close the holes 9, thereby preventing the admission of more steam. The steam now within the head and in the recess A of the packing-ring 5, which it has entered through the hole 2, pressing equally in all directions, forces the rings 4, 5, and 6 out against the interior surface of the cylinder, and, acting on the shoulders of the recesses C in the rings, forces them laterally against the piston-head P, and against the follower *m*, making all these joints steam-tight. The steam in the recess A of the ring 5 exerts a downward pressure against the interior surface of the cylinder, and an upward pressure against the ring 5, which, in turn, imparts it to the ring *w* of the head, thereby sustaining the weight of the piston-head and piston-rod, or as much of their weight as may be desired. The area of the recess A should be in proportion to the weight of the head; for instance, if the head and rod weighed two hundred pounds, with a pressure of twenty pounds of steam within the recess, and it is required to balance the whole weight, the area should be ten square inches. As the rings wear thinner between the ends of the wings *w* and the surface of the cylinder, it will be necessary to insert pieces of sheet iron or tin, as shown at the point marked *y*, in order to prevent any play or looseness among the parts. The steam contained in the grooves *f* of the rings 4 and 6, which has entered the grooves from the interior of the head through the cuts or joints 3, serves to lubricate the piston in its passage back and forth through the cylinder. When, by condensation or otherwise, the pressure of steam within the head falls below the pressure which is regulated by the difference in the areas of the ends of the piston 1, the piston 1 will again act and fill the head to the required pressure.

I wish it understood I do not confine myself to any particular size or proportions in the construction of my improved piston-head, for the same may be varied to suit the judgment of the mechanic.

Having thus described the nature, construction, and operation of my improvement, what I claim as of my invention, is—

1. The recess C between the packing-rings of a piston-head of a cylinder of a steam engine, as herein described, and for the purpose set forth.
2. The plates *g* and *h*, when used in combination with a joint or joints in metallic and expansive packing of a piston-head, as herein described and set forth.
3. In connection with the above the valve *x*, constructed, arranged, and operating substantially as herein described, and for the purpose set forth.

EDWARD SULLIVAN.
